UNITED STATES PATENT OFFICE.

WALTER H. KNIGHT, OF NEW YORK, N. Y., ASSIGNOR TO PNEUMATIC CARRIAGE CO., OF NEW YORK, N. Y., A CORPORATION OF WEST VIRGINIA.

STEAM-TRUCK.

SPECIFICATION forming part of Letters Patent No. 711,112, dated October 14, 1902.

Application filed February 25, 1901. Serial No. 48,744. (No model.)

To all whom it may concern:

Be it known that I, WALTER H. KNIGHT, a citizen of the United States, residing in the city, county, and State of New York, have invented certain new and useful Improvements 5 in Steam-Trucks, of which the following is a specification.

This invention relates to improvements in steam-trucks or motor-vehicles; and its object is to provide a truck in which the steam generating and motive members are rigidly connected together in such manner as to reduce to a minimum the difficulties usually arising from deterioration, leakage, and condensation in long pipe connections and to provide spring-support for such members, while also providing for driving connection between the motive members and the driving-wheels, which are also the steering-wheels, 15 and the driving connections are such as to allow of the turning movements of each steering-wheel on its steering-pivot.

In the accompanying drawings, Figure 1 is a longitudinal section of a motor-vehicle embodying my invention. Fig. 2 is a transverse section in the plane of the fore or steering axles with parts on one side in elevation.

I have herein shown my invention applied to a cart or truck, it being especially intended 25 for heavy work, though it is applicable to motor-vehicles generally.

1 represents the truck or running-gear frame of the vehicle, and 2 the vehicle-body, supported on the truck-frame by springs 3 3'. 35 Rear wheels 4 and fore-truck wheels 5 are provided, as usual, the said fore-truck wheels being mounted on independent steering-axles 6, pivoted to vertical spindles 7, mounted in bearings 8 in the truck-frame 1.

40 A boiler is mounted on the vehicle-body 2 by hanger-brackets or frame 9 and comprises lower water-drums 10 and one upper drum 11, extending over the water-drums and connected thereto by risers or pipes 11^a. The fire-box 12 is located below the boilers and provided with grate 13, in which are arranged pipes 13^a, connected with the boiler or with the feed-water supply. Each of the boiler-drums contains tubes 14, extending longitudinally therethrough and seated in heads 15,

a manhole 16 being arranged in the fire-box front opposite each front head 15 to enable access to said tubes. The course of the products of combustion is from the fire-box through tubes 14 and up through the stack 55 16^a. The boiler-carrying frame 9 is provided with vertical guiding-plates 17, which run on corresponding guides 18 on the truck-frame 1, so as to guide the frame 9 vertically.

Two engines 20 are rigidly mounted, one 60 on each side of the boiler, and are connected to the upper drum 11 by a common supply-pipe 21, controlled by throttle 22. Each engine has a valve whose operating-spindle is indicated at 23 and is connected by a lever 24 65 and link 25 from a controller 26, here shown as a pedal. As the engines 20 partake of the vertical movements of the vehicle-body it is necessary to provide extensible driving connections or couplings between their shafts 29 70 and the vehicle-wheels, these being here shown as cross-head devices 27 28, engaging one another, so as to permit of axial movement, but to transmit rotative movement, (by means of cross-grooves in one member engaged by cross-ribs on the other,) one of said members being connected to the main or driven shaft 29 of the compensating steam-engine, which shafts 29 are vertical and in line with the pivots 7 of the steering-wheels, 75 80 while the other member is connected to a bevel-wheel 30, pivoted on the steering-pivot 7 of the compensating steering-wheel 5 and engaging with a bevel-wheel 31 on said steering-wheel. In steering the wheels 5 are turned 85 on their pivots 7 by steering hand-wheel 32, rod 33, suitable connections situated at 34, and in such movement the connection through the bevel-wheel 30, concentric with the steering-pivot 7, enables the driving connection 90 to be maintained.

Having thus described my invention, the following is what I claim as new therein and desire to secure by Letters Patent:

1. In a motor-vehicle, the combination with 95 the truck-frame and the steering-wheels mounted on independent axles, pivoted to said truck-frame, of two independent engines spring-supported on said truck-frame and having their shafts respectively in line 100

- with the pivots of said independent axles, and independently connected to said steering-wheels through extensible connections, each consisting of sliding coupling members one of which is carried by the engine-shaft and the other is mounted on the pivot of the independent axle, such driving connections comprising a power-transmitting gear concentric with the pivots of the steering-axles.
- 10 2. In a steam-vehicle, the combination with the truck-frame, and the steering-wheels independently pivoted on said truck-frame, of the steam-engines spring-supported on said truck-frame, with vertical engine-shafts in line with the pivots of the steering-wheels and gears on said steering-wheels and gears engaging therewith and mounted concentrically with the pivots of the steering-wheels, and extensible couplings between the last-named gears and the engine-shafts.
- 15

3. In a steam-vehicle, the combination with the truck-frame, and the steering-wheels independently pivoted on said truck-frame, of the boiler, spring-supported on said truck-frame and steam-engines rigidly mounted on said boiler, with vertical engine-shafts in line with the pivots of the steering-wheels and gears on said steering-wheels and gears engaging therewith and mounted concentrically with the pivots of the steering-wheels, and extensible couplings between the last-named gears and the engine-shafts.

20 25 30
WALTER H. KNIGHT.
